UNITED STATES PATENT OFFICE

2,039,360

WARNING SIGNAL FOR VEHICLES

J. Wayne Staley, Mount Pulaski, Ill.

Application November 3, 1934, Serial No. 751,342

4 Claims. (Cl. 177—337)

This invention relates to warning signals for vehicles, and has for an object, the provision of novel means and electric circuits for controlling and operating a light signal in conjunction with or in connection with a sound signal, or broadly stated, the use of visual and audible signals for vehicles or automotive vehicles such as automobiles, air craft, or railway trains.

For purposes of illustration, the invention is here shown and described as applied to an automobile.

Another object of my invention is the provision of novel means and circuits for controlling and operating a plurality of visible and audible signals simultaneously from a single source by one operation.

A further object of the invention resides in the provision of means for selectively controlling and operating from a single source one or more visible signals simultaneously with one or more audible signals or for operating the visible signals independently of the audible signals or vice versa.

With the above and other objects in view, my invention consists in the novel combination of the parts or apparatus and in the electric circuits and control therefor, shown in preferred embodiments in the attached drawing, described in the following specifications and particularly pointed out in the appended claims.

In the illustrations:

Fig. 1 is a schematic illustration of a circuit and apparatus embodying my invention as applied to an automobile.

Fig. 2 shows a schematic illustration of circuit and a combined selector switch and push button operator.

Fig. 3 is a vertical section through the selector switch and push button operator.

Fig. 4 is a cross section taken on line 4—4 of Fig. 3.

Fig. 5 is a fragmentary view of the combined switch portion, showing the limit pin and arcuate slot therefor.

In the illustrations:

X indicates a switch or push button; Y indicates a three position selector switch; Z indicates a relay; A indicates signal lights; B indicates horns or other sound devices; and C indicates a battery or other source of electric energy.

In the circuit shown in Fig. 1, the switch or push button X is connected through the conductor 10 to one of the post connections of the relay Z and the other post connection of the relay 55 is grounded to the frame of the vehicle. The

conductor 11 connects the other terminal contact of the switch X with the positive terminal of battery C. The negative terminal of the battery being grounded.

The light signals A are grounded through conductors 12 and their other terminals are connected through conductors 13 to the movable switch arm 14, which is adapted to contact either terminal 15 or terminal 16 of the switch.

The switch terminal 15 is connected through conductor 17 to a movable terminal 18 of the relay Z, and the terminal 16 is connected through conductor 19 to terminal 20 of the relay.

Each of the horns B has one connection ground through a conductor 21 and the other connections of the horns B are connected through conductor 22 to terminal 23 of the relay Z and a co-operating terminal 24 of the relay is connected through the conductor 25 to the positive terminal of the battery C. The positive terminal of the battery C is also connected through conductor 26 to the terminal 16 of the switch Y and with the terminal 20 of the relay through its connection with the conductor 19.

Through the circuit and devices shown in Fig. 25 1, three operations of the system are possible, namely:

Operation 1.—When the switch arm 14 of switch Y is in neutral position, as shown in full line, the circuit to the lights A is open, hence an operation of the push button switch X will close the battery circuit through relay Z and through its terminals 23 and 24 causing an operation of the horns B only.

Operation 2.—When arm 14 of switch Y is moved into position to close the circuit through terminal 15 as shown by the dotted lines, an operation of the push button switch X will close the battery circuit through relay Z and through its terminals 23 and 24, and through its terminals 18 and 20 thus causing a simultaneous operation of both light and horn signals.

Operation 3.—When arm 14 of switch Y is moved into position to close the circuit through terminal 16, as shown by the dotted lines, an operation of the light signals A will be immediately effected without the use of the switch X since the circuit for the lights A will be closed to the battery through conductors 19 and 26. An operation of switch X will cause the operation of the horn B in conjunction with the light signals A if so desired.

My invention contemplates the use of sound or audible devices which are adapted to be operated by electric current, vacuum or air pressure. 55

Referring now to Figs. 2 to 5 inclusive, which illustrate the combined selector switch and push button operator as applied to the end of a steering post 30, a cylindrical body member 31 is provided which is screw-mounted to the end of the steering post 30. The body 31 is cast with a cross wall 30^A which is provided with a central opening to receive the movable tubular switch member 32.

The tubular switch member 32 of electrically non-conductive material is provided with an interior cross wall 32^A having a central opening for a push button pin 33 the upper end of which is enlarged as at 33^A and secured within the push button head 34.

15 The tubular switch member 32 is also provided with a circular lateral flange 32^B which is rotatably supported on top of the body member 31.

A central apertured cap 35 is screw-mounted on the body member 31 and retains the flange 20 32^B against vertical displacement.

A plug 36 may be screw-mounted within the lower end of the tubular member 32 as a closure member.

The enlarged pin portion 33^A extends through 25 a central opening within circular disk operator 37 for the tubular switch member 32, which switch member 32 is secured to the disk 37 by its screw engagement with the circular collar 37^A of the disk 37.

30 Within the supporting body member 31, I mount a cylindrical member 38 of electrically non-conductive material which is securely held in place by a ring 39 screw-mounted in the lower end of member 31.

35 The cylindrical member 38 is formed with a lateral wall 38^A at one end thereof and is provided with a central opening for the tubular switch member 32.

40 Mounted within the member 38 and to its cylinder wall are a pair of spring contact plates 40 and 41 to which are secured respectively conductors 10 and 11, see Figs. 2, 3 and 4. The contact plate 41 is normally held in spaced or open switch position and is adapted to be moved into 45 closed position in contact with plate 40 by means of a pin 42 which is slidable through the wall of the tubular switch member 32 by means of its pivotal connection with a small bell crank 43 which is pivotally supported on the inside of the 50 member 32 and provided with a forked end for engagement about the pin 33 between a pair of nuts thereon.

The push button 34 performs the same function as push button X in the circuit in Fig. 1, 55 and is normally held in raised or open position by means of a coil spring 44 interposed between the wall 32^A and the enlarged pin portion 33^A.

The electrically non-conductive support 38 is also provided with three spaced spring contacts 60 15, 27 and 16 to which are connected respectively conductors 17, 13 and 19.

A movable contact spring 45 fixed to the exterior of member 32 is adapted to be moved into position to close the circuit between contacts 15 65 and 27 or between contacts 16 and 27. When the contact 45 is only in contact with the contact 27 the switch is in neutral or open position and this position corresponds to the position of the switch arm 14 of switch Y, as shown in full lines in Fig. 1.

70 The two positions of the switch contact 45, wherein the circuit is closed between contacts 15 and 27 or between contacts 16 and 27, are controlled by the movement of the disk 37 and its interconnected switch member 32 within the limits of the movement of pin 46 with the arcuate

slot 47 of the cap 35, see Figs. 3 and 5. The pin 46 being securely mounted within the flange 32^B.

It is believed that the operation of the combined selector switch and push button will be readily understood from the above description 5 and diagram of the circuit in Fig. 2.

The use of the relay Z in the circuits shown permits the battery leads to be of the least possible length thus reducing the resistance to the minimum.

10 I prefer to use a relay with two sets of contacts to permit the light and sound devices to operate over separate parallel paths to thus reduce the circuit resistance to a minimum, since many of the modern types of sound devices have a comparatively high current drain and circuit resistance interfered with tone, pitch and tuning.

While the relay might be omitted in the circuits shown, unusually heavy conductors would be required for the simultaneous operation of both 20 light and sound devices.

The visual or light signals may be mounted on the vehicle in any desired location thereon, as for instance on the front and rear ends and on the sides thereof, and the lights may be of any desirable color, as for instance amber, orange, yellow or green.

I claim:

1. In a circuit for warning signals for vehicles, a visual signal, an audible signal, a relay having 30 two sets of contacts, a battery, a three position switch, a push button switch, said visual signal and audible signal and relay and battery having connections with a common ground element, a conductor connecting said visual signal with a movable switch arm of said three position switch, a conductor connecting said audible signal with one connection of one of said sets of relay contacts and a conductor connecting the other connection of said one of said sets of relay connections with the battery, a conductor connecting said push button switch with a terminal of said relay, a conductor connecting said push button switch with said battery, said three position switch having a pair of contacts, a pair of separate conductors connecting said pair of three position switch contacts with a pair of contacts on said relay, and a conductor connecting one of said conductors of said three position switch with said battery. 50

2. In warning signal devices for vehicles having an audible signal and a visual signal, a circuit including a single source of energy, a three position double contact selector switch, and a single contact push button switch, said circuit being so arranged that when said selector switch is in neutral position the audible signal is adapted to be operated by said push button switch, said selector switch being adapted to be moved to a contact position to operate the visual and audible signals by operation of the push button switch, and when said selector switch is moved to another contact position, other than said neutral or first named contact positions, said push button switch being adapted to solely and simultaneously operate both visual and audible signals. 65

3. In a circuit as embodied in claim 2, and including a double contact relay providing separate parallel energy paths for said audible and visual signals to thereby lower the circuit resistance to 70 a minimum.

4. In warning signal devices for vehicles having an audible and a visual signal, a circuit including a single source of energy, a double contact selector switch, a double contact relay pro- 75

viding separate parallel energy paths for said audible and visual signals to thereby lower the circuit resistance to a minimum, and a single contact push button switch, said circuit being so arranged that when the selector switch is moved to one contact position both audible and visual signals may be simultaneously operated only by

said push button switch, a movement of said selector switch to the other contact position will cause an operation of the visual signal independently of said audible signal and an operation thereafter of the push button switch will cause both visual and audible signals to operate. 5
